UNITED STATES PATENT OFFICE.

EDWIN J. SONN, OF NEWARK, NEW JERSEY, ASSIGNOR TO EASTERN BOTTLEDERS SUPPLY COMPANY, OF NEW YORK, N. Y., A CORPORATION OF NEW YORK.

DESIGN FOR A LABEL-BLANK.

43,028.

Specification for Design.

Patented Sept. 17, 1912.

Application filed July 15, 1912. Serial No. 709,583. Term of patent 7 years.

To all whom it may concern:

Be it known that I, EDWIN J. SONN, a citizen of the United States, residing at the city of Newark, Essex county, in the State of New Jersey, have invented a new, original, and ornamental Design for a Label-Blank, of which the following is a specification, reference being had to the accompanying drawing, forming part thereof, showing a label-blank embodying my said design.

I claim:

The ornamental design for a label blank, as shown.

EDWIN J. SONN.

Witnesses:

JNO. W. JACOBUS,
JOSEPH G. QUINN, Jr.
